UNITED STATES PATENT OFFICE.

JOHN THOMAS PRIOR, OF PRIOR'S STATION, GEORGIA.

PLOW.

SPECIFICATION forming part of Letters Patent No. 366,128, dated July 5, 1887.

Application filed March 23, 1887. Serial No. 232,146. (No model.)

To all whom it may concern:

Be it known that I, JOHN THOMAS PRIOR, a citizen of the United States, residing at Prior's Station, in the county of Polk and State of Georgia, have invented certain new and useful Improvements in Plows; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to half-shovel plows, and my object is to form one which will be stronger, more durable, and better braced than those now in common use.

In the accompanying drawings, making part of this specification, Figure 1 represents a blank from which the shovel is made, and Fig. 2 is the complete shovel-blade.

In the figures, A represents the blade of the shovel, which has a V-shaped flange, B, rolled upon one edge, and which is an integral part of it. When the blade has been rolled for use, its lower or cutting edge is sharpened or beveled to cut. The edge of the flange is sharpened and beveled to readily enter and cut the earth, as seen at a b. The flange forms a strong brace on the edge of the blade to keep it in shape and at the same time assist in cutting when working in hard ground.

It will be observed that the lower part, b, of the cutting-edge is rounded, and from its terminal angle the edge of the blade is directed backward, so as to produce a shear-cut.

The essential feature of my invention con-

sists in first rolling a flat plate of metal with a beveled angular cutting portion, B, the sheet of metal on which this angular cutting portion is formed being of any desired length. This plate is then cut in proper lengths to form a plow. The sections cut from said blank are then subjected to suitable machinery, which cuts the lower end of shear part of 45 of the blank obliquely, bevels it to form the cutting-edge a, and also rounds off the lower terminus of the fin at b, and bevels it to form a shear cut at this point.

I am aware that it is not new to prepare 50 plow-plates by rolling them in blanks of various forms and of unequal thickness and then cutting the blanks to the desired size and shape. I am also aware that plow shovels and scrapers have been common with flanges or 55 cutting-edges made integral and compressed to the proper shape. I therefore claim only the exact form and product of my especial methods.

Having thus fully described my invention, 60 what I claim as new, and desire to secure by Letters Patent, is—

A shovel-plow consisting of a curved shovel-body, A, having a cutting-fin, B, on the land-side edge, condensed as described, the rounded 65 cutting-terminal portion b of this fin, and the oblique cutting portion a of the body portion, substantially as described.

In testimony whereof I affix my signature in presence of two witnesses.

JOHN THOMAS PRIOR.
